United States Patent Office

Des. 219,623
Patented Dec. 29, 1970

219,623

TELESCOPE

David P. Bushnell, 2124 Midlothian Drive,
Altadena, Calif. 91001

Filed Oct. 20, 1969, Ser. No. 19,648

Term of patent 14 years

Int. Cl. D16—08

U.S. Cl. D57—1

FIG1

FIG6

FIG3

FIG2

FIG. 1 is a perspective view of the telescope, showing my new design,

FIG. 2 is a front elevational view of the telescope,

FIG. 3 is a rear elevational view of the telescope,

FIG. 4 is a left side elevational view of the telescope,

FIG. 5 is a right side elevational view of the telescope, and

FIG. 6 is a fragmentary sectional view taken substantially along the plane of the line 6—6 of FIG. 4.

I claim:

The ornamental design for a telescope, as shown.
